UNITED STATES PATENT OFFICE

115,133

DESIGN FOR A COMBINED TOOTH BRUSH AND POWDER HOLDER

Bessie L. Short, Ames, Iowa

Application April 21, 1939, Serial No. 84,482

Term of patent 14 years

To all whom it may concern:

Be it known that I, Bessie L. Short, a citizen of the United States of America, residing at Ames, in the county of Story and State of Iowa, have invented a new, original, and ornamental Design for a Combined Tooth Brush and Powder Holder, of which the following is a specification, reference being had to the accompanying drawing, forming a part hereof.

In the drawing:

I claim:

The ornamental design for a combined tooth brush and powder holder, as shown.

BESSIE L. SHORT.
